UNITED STATES PATENT OFFICE

GAY PRENTICE BLESSING, OF SEATTLE, WASHINGTON.

TELEGRAPH APPARATUS.

1,108,545.

Specification of Letters Patent. Patented Aug. 25, 1914.

Application filed August 18, 1913. Serial No. 785,386.

To all whom it may concern:

Be it known that I, GAY PRENTICE BLESSING, a citizen of the United States of America, and a resident of the city of Seattle, in the county of King and State of Washington, have invented certain new and useful Improvements in Telegraph Apparatus, of which the following is a specification.

10 This invention relates to electrical apparatus and more particularly to a means for reversing the polarity of the battery on a telegraph line, when such battery is at a distant station, it having for one of its objects 15 to provide such an apparatus which will operate in an efficient manner and be of simple construction.

A further object resides in means adapted for single line wires whereby polarized relays may be utilized at all intermediate or

20 way stations. Other objects will appear as my description progresses, and for a full understanding of the invention reference is to be had to the 25 following specification, the appended claims and the accompanying drawings wherein—

Figure 1 is a diagrammatic view illustrating my invention as employed in a telegraph line. Fig. 2 is a side elevation of my 30 duplex relay. Fig. 3 is an end elevation, and Fig. 4 is a polarized relay employing a spring to aid in opening the sounder circuit.

I have illustrated my invention being employed for reversing the polarity of a battery of a telegraph on a single line wire but the same may be utilized for various purposes.

In modern telegraphy, the trouble experienced with the common relays employed is that on account of the current escaping to the earth at the various supports, leaves of trees resting on the wires, and such like, along the route, and especially in wet weather, it is impossible for the operator at 45 a station distant from the battery station to cut off all of the current passing through the instruments at the stations between him and the battery station. Thus, the greater the distance of a station from the battery station, the lesser the amount of current which 50 passes through the instruments at that station owing to the loss or escape of the current as above indicated. While it is not necessary that all the current should be cut off, as each relay is provided with a retractile spring and other means of adjust- 55

ment so that as the escape of current increases owing to the increase in rainfall adjustment may be made accordingly, still in practice it is a very common occurrence for 60 a large majority of the stations or instruments to be out of adjustment when it starts to rain, and as the rain increases constant attention must be given the instruments in order to keep them so adjusted as to hear 65 what is going on over the wire.

By using my invention, polarized relays 70 may be utilized on single line wires and enable the operator at any station to reverse the polarity of the main battery to thereby 75 actuate the armatures of the polarized relays at all stations. Thus, the efficiency of the wires would be increased by the utilization of polarized relays, especially in wet weather, and do away with the trouble now 80 experienced, of the instruments at the way stations being out of adjustment when it rains, as by this system the only instruments which would need to be adjusted would be those located at the battery stations where 85 the attendants are much more skilled in this respect than the average operator. The instruments at the way stations will require no adjustment after a proper installment regardless of the quantity of current escaping. 90

Referring in detail to the accompanying drawings, 1 designates a suitable base or support having mounted thereon an upright support 2 for carrying the relay coils 3 which are adjustable by screw member 4 95 and have the armature 5 pivoted to base 1 to be attracted by the said coils against the tension of the variable tension member 6. The movement of the armature may be controlled by the screw 7 as is obvious. When 100 attracted by coils of magnet 3, armature 5 makes contact with platinum contact point 8 on upright 2, said contact 8 being connected to a binding post 9 while the armature is connected to a binding post 10. A platform 11 supported above the base carries a locking armature 12 which is urged downwardly by a spring 13 and adapted for attraction by a superposed magnet or relay coils 14 which latter are connected to binding posts 105 on the platform. The armature 12 is pivoted as at 16 and is in metallic connection with armature 5 through wire 17. Locking armature 12 is formed with a shoulder 12' which falls down back of contact arm 5' of armature 5 projecting upwardly through a slot 18 provided in the platform 110

when armature 5 is attracted by coils 3, such dropping of the locking armature being aided by the spring 13. Thus, when the current passing through the coils 3 is 5 cut off, locking armature 12 will practically retain armature 5 against contact 8 for closing the circuit between binding posts 9 and 10. Of course, too much friction between contact arm 5' and shoulder 12' must 10 not be provided. However, should there be too much play between them, the circuit will still remain closed between the binding posts 9 and 10 since armature 12 engages platinum contact 19 when it locks armature 15 5, said contact being in metallic connection with contact 8. When a current passes through coils 14, armature 12 is drawn up to release armature 5 and when the current is cut off from coils 14, the locking armature is released, its shoulder 12' falling on 20 top of the contact arm 5' in which position the armatures do not contact with the contacts 8 and 19. Upon energizing magnet 3 armature 5 is attracted to allow shoulder 25 12' falling behind the end portion 5' as above set forth. Current wires for energizing magnet 3 are fastened to binding posts 20. One of these instruments is located at each battery station and by reference to the 30 diagrammatic view, a thorough understanding of the utility and operation of my duplex relay may be obtained. The current passing through the main line 50, when sending a message, energizes magnet 3 which 35 attracts its armature 5 to close the local circuit A. This circuit includes the armature 5, the contact points 8 and 19, an electro-magnet 51 connected, as by conductor 52, to the contact points, a "pole changer" 40 electro-magnet 53 connected to armature 5 by conductor 54 and a battery 55 connected to the magnets 51 and 53. Energizing magnet 3 will close the local circuit A by armature 5 engaging contact 8. Closing this 45 circuit will energize magnets 51 and 53 which will attract their armatures 56 and 57, respectively. Armature 56 is included in a second local circuit B which further consists of a battery 58 and the 50 magnet 14, of the duplex relay, connected by conductors. Two batteries 60, 61, are provided, at the battery station, for the main line, one of which has its negative pole grounded and the other having its positive 55 pole grounded, as by conductor 59. The other pole of each battery is connected by a conductor which is comprised in the term "battery" and terminates in a suitable contact point for engagement by the armature 60 57, which I term a "pole changer."

When the operator opens his key to send a message, the various instruments assume the position shown in the diagrammatic view, which I have called "normal" position. The pole changer at one battery sta-

tion is in connection with a positive pole, while the pole changer at the other station is connected to the negative pole, for obvious reasons. When magnet 53 attracts the pole changer armature, the latter breaks the circuit with one battery and makes connection with the opposite pole of the other battery, thereby changing the polarity of the battery along the line. Upon energizing magnet 3, which is connected by the line wire 50' to the pole changer 57, magnet 53 is energized also, as its circuit is closed by armature 5. Without the locking armature the following operation would result: In attracting the pole changer from its normally engaged 70 contact, the circuit is broken, the current cut off, and the magnet 3 deenergized whereby local circuit A is broken by the releasing of armature 5 which causes magnet 53 to become deenergized. The pole 75 changer, not having had sufficient time to cross the gap between the pole terminals of the batteries, is urged to its normal position by spring 62 which closes the main circuit again and another cycle of operation follows with a continual buzzing of the two armatures as a result. By employing the locking armature, the local circuit is maintained closed until the pole changer has had sufficient time to cross the gap or space between the pole terminals of the batteries to 80 reverse the polarity. The reversed current energizes magnet 3 to maintain the current reversed until the operator releases the key to break the circuit. In energizing magnet 85 53 initially, magnet 51 becomes energized to also attract its armature 56 for closing local circuit B. Magnet 14 then becoming energized draws up locking armature to permit the armature 5 to fall back, being 90 urged by spring 6, when the main circuit is broken. However, before the locking armature is elevated by its magnets, the pole 95 changer has crossed the gap and the magnet 3 is energized by the reverse current. This 100 magnet being energized, its armature is held in the closed position maintaining local circuit A and the magnet 53 energized to hold its armature to the attracted position. Now 105 considering the way or intermediate stations other than the battery stations, each is provided with a polarized relay 70, in the main line 50, and a local circuit C including the armature 71 of the relay, a sounder 72 and battery 73. At each station is provided 110 also, a suitable resistance 74 connected in parallel with the key 75.

The keys at all the stations are normally closed with the exception of the one from which the message is being sent. By pressing the key, the operator closes the circuit and reverses the polarity of the battery along the line, thereby causing the armature of the polarized relay to move to close the local circuit C and operate sounder 72. 115 120 125 130

Upon releasing the key and breaking the circuit, magnet 3 becomes deenergized breaking local circuit A and spring 62 pulls pole changer across the gap to send a reverse current along the main line to reverse the action of the polarized relays on their armatures, *i. e.*, repel the armatures and break the local circuits C. This current passes through resistance 74, the key being opened, which weakens the current sufficiently to prevent the energizing of magnets 3 enough to attract armatures 5 against springs 6. Thus, it will be seen that the resistance provides a path for the weakened reverse current to push or repel the armatures of the polarized relays to an "opened" position.

By providing a retractile spring 100 of sufficient strength to overcome the tendency of the armature to remain closed on account of what residual magnetism there may be in the magnet, the resistance may be done away with. In this instance, whatever escape current passes through the instrument would assist the spring to open the relay and the more the escape, the more vigorously would the armatures come back to the open position which is exactly the opposite action of the common relays now employed.

The duplex relay instrument may be employed in various ways, as, for instance, an automatic repeater between two or more of the polarized circuits above described with battery at one end only, which may be accomplished by changing the manner of connecting the local circuits.

I am aware that various modifications from the construction herein described may be made without departing from the spirit and scope of my invention as claimed, and so I do not wish to be understood as limiting myself by the specific terms herein employed excepting as the prior art may require.

By slightly modifying the construction, the instrument may be employed as an automatic repeater between two "Morse" circuits at any station, either at battery station or a station distant therefrom, and as such requires no local battery.

Having thus described my invention, what I claim as new, and desire to secure by Letters Patent of the United States of America, is:—

1. In an instrument of the character described, a relay comprising an electro-magnet and an armature, a contact arm operable by the armature, contact means mounted for engagement by the contact arm for closing a circuit, means for locking the arm against the contact means, said locking means being in metallic connection with the contact arm and adapted for engagement with the contact means, and means for releasing the arm from the locking means.

2. In an instrument of the character de-

scribed, a relay comprising an electro-magnet and an armature, contact means, an arm operable by the armature for engagement with the contact means for closing a circuit, a second relay comprising an electro-magnet and an armature, means for locking the first armature against the contact means and releasable by the second armature, said locking means being in metallic connection with the arm and adapted for engagement with the contact means.

3. In combination, electrical energy supply means, a pole changer normally connected with one pole of the supply means and adapted to connect with the opposite pole of the latter, an electro-magnet for moving the pole changer, a local circuit including the magnet and normally maintained opened, a main circuit including the supply means and pole changer, a second electro-magnet included in the main circuit, means for closing the local circuit operated by the second magnet when a certain amount of current passes through the latter for energizing the same, and means for controlling the current through the main circuit.

4. In combination, electrical energy supply means, a pole changer normally connected with one pole of the supply means and adapted to connect with the opposite pole of the latter, an electro-magnet for moving the pole changer to connect with the last named pole, means for returning the pole changer to normal position when released by the magnet, a local circuit including the magnet and normally maintained opened, a main circuit including the supply means and pole changer, a second electro-magnet included in the main circuit, means for closing the local circuit operated by the second magnet when a certain amount of current passes through the latter for energizing the same, and means for controlling the current through the main circuit.

5. In combination, electrical energy supply means, a pole changer normally connected with one pole of the supply means and adapted to connect with the opposite pole of the latter, an electro-magnet for moving the pole changer, a local circuit including the magnet and normally maintained opened, a main circuit including the supply means and pole changer, a second electro-magnet included in the main circuit, means for closing the local circuit operated by the second magnet when a certain amount of current passes through the latter for energizing the same, a telegraph key for operation in the main circuit, a polarized relay in the main circuit, a sounder, and a circuit including the sounder and polarized relay closed by the latter.

6. In combination, electrical energy supply means, a pole changer normally connected with one pole of the supply means

- 4 and adapted to connect with the opposite pole of the latter, an electro-magnet for moving the pole changer, a local circuit including the magnet and normally maintained opened, a main circuit including the supply means and pole changer, a second electro-magnet included in the main circuit, means for closing the local circuit operated by the second magnet when a certain amount of current passes through the latter for energizing the same, means for retaining the local circuit closed, a second local circuit closed by the closing of the first local circuit, an electro-magnet included in the second local circuit and adapted to move said retaining means to permit the opening of the first local circuit, and means for controlling the current through the magnet of the main circuit.
- 5 20. 7. In combination, electrical energy supply means, a pole changer normally connected with one pole of the supply means and adapted to connect with the opposite pole of the latter, an electro-magnet for moving the pole changer, a local circuit including the magnet and normally maintained opened, a main circuit including the supply means and pole changer, a second electro-magnet included in the main circuit, means for closing the local circuit operated by the second magnet when a certain amount of current passes through the latter for energizing the same, means for engaging the last means for retaining the local circuit closed, an electro-magnet for moving the retaining means to release the local circuit closing means, a second local circuit including the
- 6 10 last electro-magnet, and means for closing the second local circuit operable on the closing of the first local circuit.
- 7 15 8. In combination, electrical energy supply means, a pole changer normally connected with one pole thereof and adapted to be moved to connect with the opposite pole and disconnect with the first pole, a telegraph key, means for moving the pole changer operable on closing of the telegraph key, a main circuit including the key, supply means and pole changer and connected to said pole changer moving means, a polarized relay in the main circuit, an electrically operated instrument, and a local circuit including the instrument and relay and closed by the latter.
- 8 20 9. In combination, electrical energy supply means, a pole changer normally connected with one pole thereof and adapted to be moved to connect with the opposite pole, an open circuit including the pole changer and supply means, means for moving the pole changer on closing the circuit, a polarized relay in the circuit, the armature of the said polarized relay being operable in one direction on closing the circuit, and means to effect movement of the polarized relay armature in a reverse direction upon opening the circuit.

Signed at Seattle, Washington, this 31st day of July 1913.
